DESIGN FOR A SWITCH HOUSING FOR FLASHLIGHTS

Orville T. Wood, Clinton, Mass., assignor to
Blake Manufacturing Corporation, Clinton,
Mass., a corporation of Massachusetts

Application May 14, 1937, Serial No. 69,353

Term of patent 7 years

To all whom it may concern:

Be it known that I, Orville T. Wood, a citizen
of the United States and a resident of Clinton,
county of Worcester, and State of Massachusetts,
have invented a new, original, and ornamental
Design for a Switch Housing for Flash-
lights, of which the following is a specification,
reference being had to the accompanying draw-
ing, forming part thereof.

Fig. 1 is a plan view of a switch housing for
flashlights showing my new design.

Fig. 2 is a side elevation; and

Fig. 3 is an end elevation as seen from the
right of Figs. 1 and 2.

I claim:

The ornamental design for a switch housing
for flashlights as shown.

ORVILLE T. WOOD.
